UNITED STATES PATENT OFFICE

LE ROY W. FAIRCHILD, OF NEW YORK, N. Y.

DESIGN FOR PENCIL-CASES.

Specification forming part of Design No. **11,418**, dated September 16, 1879; application filed August 7, 1879.
[Term of patent 7 years.]

To all whom it may concern:

Be it known that I, LE ROY W. FAIRCHILD, of the city, county, and State of New York, have produced a new and original Design for Small Implement Cases, including watch-keys, pencils, and the like, intended to be worn upon a chain, of which the following is a full, clear, and exact description thereof, reference being had to the accompanying engraved illustration, making a part of this specification.

The invention consists in forming the lower section of the case to represent a pedestal and the upper part to represent an owl standing upon the pedestal, which may be done not

only in form but in color by different metals or grades of metal, or by enamels, or otherwise.

A represents the design as a whole. b is the stem-ring. c is the pedestal. d is the figure of an owl; and the whole forms a pencil or other small implement case.

What I claim as my invention is—

A design for a pencil-case, consisting of an owl standing upon a pedestal, as shown in the illustration A, substantially as above described.

LE ROY W. FAIRCHILD.
